corporation of Delaware

Application May 22, 1939, Serial No. 275,007

5 Claims. (Cl. 290—38)

This invention relates to ignition systems for automotive internal combustion engines and more particularly to the problem of obtaining flat contact operation in an automotive ignition system.

I have discovered that transfer of contact metal to the ignition timer is due to a phenomenon which occurs during each separation of the timer contact. This phenomenon is beyond the control of those who design and install the ignition system. I have found that transfer of contact metal to the positive timer contact is due to a phenomenon which is within the power of the designer or installer to control. In my pending application, which has now become Patent No. 2,189,899 of February 13, 1940, I propose to deal with the problem of flat contact operation by balancing negative contact transfer with positive contact transfer which I am able to control to a substantial degree. In the case of passenger car service, for example, where the engine operates over a relatively wide range of speeds, I overcompensate for negative transfer during the lower speeds of driving for example around 25 M. P. H. and under compensate at higher speeds so that, taking a period of automobile operation which represents the average of driving conditions, I am able substantially to balance negative contact transfer by transfer to the positive.

I aim to effect substantially flat contact operation by a different method which I disclose in the present application. Instead of providing positive contact transfer to compensate for negative contact transfer I so construct and arrange the ignition system that only transfer to the negative contact will occur at any speed of the engine. It is my belief that each instance of negative contact transfer is substantially less than each instance of positive contact transfer. Therefore in my new method I propose to deal only with negative contact transfer. In order to compensate for transfer to the negative contact, I propose to reverse the polarity of the contacts by means of a polarity reversing switch which will change the polarity of the contacts each time the ignition is turned on by a manual switch, or to automatically reverse the polarity by a switch which is operated concurrently with the use of the engine starter.

While I recognize that the use of polarity switches is old for the purpose of attempting to compensate for contact pitting and coning, I claim to be the first to have eliminated the positive contact transfer in an ignition system where

5 polarity reversing is employed. So far as I am aware, when polarity reversing switches have been used in ignition system in the past, no attention whatever was paid to the phenomena which caused contact metal transfer. When the timer contacts were connected for one polarity and the ignition system was operated, it is my belief that positive contact transfer has occurred as well as negative contact transfer during the time that 10 the timer contacts were connected up for a certain polarity. Then, when the polarity was reversed, there would have been positive contact transfer as well as negative transfer again under the conditions of reversed polarity. Apparently 15 no one was aware of the fact that both kinds of transfer were taking place while the polarity of primary current remained the same. Hitherto, it was supposed that the direction of contact metal transfer was always the same until the 20 polarity of the contacts had been reversed.

Since I have discovered that negative contact transfer appears to be less in quantity than positive contact transfer, for each instance of transfer of its kind, I take advantage of the fact that 25 transfer to the negative is the lesser of the two evils and design and arrange the system so that I obtain only negative transfer. As stated before, I obtain a balance at least to a practical degree by polarity reversing at intervals sufficiently frequent to effect a balance between negative transfer in one direction and negative transfer in the other direction.

Further objects and advantages of the present invention will be apparent from the following 30 description, reference being had to the accompanying drawing, wherein a preferred embodiment of one form of the invention is clearly shown.

In the drawing:

40 Fig. 1 is a diagram of an electrical system for automotive use embodying the present invention.

Fig. 2 shows the polarity reversing switch of Fig. 1 in a different position.

45 In the drawing, 20 designates a storage battery which is grounded at 21. The battery is charged by the usual automotive generator not shown. Battery supplies current for engine ignition and for engine starting. The main starter circuit is shown in heavy lines and comprises a wire 22 leading to a starter switch terminal 23. The other starter switch terminal 24 connected by a wire 25 with a series wound starting motor 26 grounded at 27. The motor operates a shaft 28 along which slides a starter drive 30 having a 50 longitudinal spline connection with the shaft 28

and including a one-way or overrunning clutch 31 for connecting the shaft 28 with a pinion 32 movable into mesh with the flywheel gear 33 of the engine to be started. The drive 30 is moved along the shaft by a lever 34 pivoted on a stud 35 and urged by a spring 36 normally into the position shown wherein the pinion 32 is out of engagement with the flywheel 33. The apparatus for shifting the lever 34 and for completing the motor circuit is disclosed particularly in John B. Dyer Patent 2,005,723, granted Jan. 18, 1938. This apparatus comprises an electromagnet 40 having a coarse winding 41, which is the main attracting winding, and a holding winding 42 of finer wire. One end lead 43 of winding 41 is connected with a relay contact 44, the other end of winding 41 is connected by a wire 45 with motor switch terminal 24. The holding coil 42 is connected at one end with ground at 46 and by wire 47 with relay contact 44. Relay contact 44 is adapted to be engaged by movable contact 48 carried on the end of an armature 49 spring urged into contact open position and against a stop 50. Relay armature 49 is magnetizable and is attached to one end of a metal frame 51 supported upon the terminal 23 and providing an electrical connection between the contact 48 and the switch terminal 23. The relay includes a core 52 surrounded by an electric magnet winding 53 grounded at 54.

The electromagnet 40 includes also a core or stationary magnetizable body 60 and a movable magnetizable body 61 or plunger connected by a link 62 having a pin 63 received by a slot 64 in the lever 34. When the magnet 40 is energized, the plunger 61 will move toward the left so as to move the lever 34 counterclockwise in order to shift the pinion 32 into mesh with the engine gear 33. This movement of the plunger 61 causes the motor switch to be closed so that the motor 26 will operate on current from the battery 20 to effect the cranking of the engine. The motor switch comprises a movable contact 70 insulatingly supported by rod 71 which is guided for sliding movement by the core 60. The rod 71 has a shoulder 72 which stops movement of the rod 71 toward the right in which direction it is urged by a spring 73 engaging a stationary part 74 and pressing against a shoulder 75 provided by the rod 71. Between the shoulders 72 and 75 of the rod 71 the insulation piece 70a which supports the contact 70 is mounted for sliding movement. Normally the insulation piece 70a is pressed by the spring 76 against the stop shoulder 75. When the magnet is energized, movement of the plunger 61 causes the rod 71 to move toward the left to carry the contact 70 into engagement with the switch terminals 23 and 24. The rod 71 is moved a little further than the normal distance between the contact 70 and the terminals 23 and 24 so that, thru the spring 76 which is additionally compressed, the contact 70 will be held in firm engagement with the terminals 23 and 24.

The operation of electromagnet is effected in response to the operation of the automobile accelerator pedal, providing the engine is not self operating. For this purpose there is provided an accelerator-pedal-closed and engine-suction-opened switch 80 having one terminal 81 connected with the relay coil 53 and the other terminal 82 connected with a switch contact 83 which is one of three equiangularly spaced stationary contacts 83, 84 and 85 adapted to be concurrently connected by the movable contact 76

86 of the ignition switch. After the switch 86 is closed, the engine being nonoperative, the car driver then steps on the accelerator pedal which causes a lever 88 of the switch 80 to move in such direction as to close the switch 80 whereupon the relay coil 53 will be connected with the battery 20 and the armature 49 will be moved downwardly to cause contact 48 to engage contact 44. When this happens both magnet coils 41 and 42 will be connected with the battery and the plunger 61 will be attracted toward the left to cause the motor pinion 32 to engage the engine gear 33 and the motor switch contact 70 to engage the terminals 23 and 24 whereupon the motor 26 will be connected with the battery to start the engine. During the cranking of the engine by the motor 26, the main attracting coil 41 is short circuited but the electromagnet maintains the plunger 61 in the attracted position by the magnetism provided by the holding coil 42. When the engine becomes self operative the suction developed by the engine is sufficient to cause the switch 80 to be opened whereupon the magnet 53 will be disconnected from the battery, the relay contacts 48 and 44 will open, the magnet 40 will be deenergized and the plunger 61 will be returned to its normal position thru the action of the spring 36 which acts directly upon the lever 34. Then the motor will be disconnected from the battery and the pinion 32 will be demeshed from the engine gear 33.

It will be noted that for each engine starting operation that is produced by the operation of the electromagnet 40 there will be a reciprocation of the link 62. I take advantage of this movement of the link 62 to operate a polarity reversing switch in the ignition system which I will now describe. The ignition system comprises an ignition coil having a primary winding 100 connected at one end with ignition switch terminal 85 and at the other end with terminal 121 of polarity reversing switch 120. The ignition coil has a secondary winding 101 connected at one end with ground and at the other end with the center terminal 102 of an ignition distributor 103 which includes a rotor 104 for distributing sparking impulses to spark plug cable terminals 105 each connected by a cable with a spark plug 106 which is grounded thru the engine as indicated at 107.

The ignition timer includes a cam 110 driven by the engine thru a shaft which drives also the rotor 102. The cam 110 is engageable with the rubbing block 111 carried by a lever 112 which is pivoted at 113 and which carries a contact 114 engageable with a contact 115. Lever 112 is connected electrically with a terminal 116 by a spring 117 which urges the lever 112 toward the cam 110. A condenser 118 is in parallel with the contacts 114 and 115. Timer terminal 116 is connected with reversing switch terminals 122 and 123. Terminal 124 is grounded and therefore is always of negative polarity. Contact 121 is always of positive polarity. The contact 125 which is connected with timer contact 115 will be of negative polarity when connected with contact 124, as shown in Fig. 1, or of positive polarity when connected with contact 121, as shown in Fig. 2. Likewise timer terminal 116 will be of positive polarity when positive contact 121 is connected with contact 122 as shown in Fig. 1; and timer terminal 116 will be of negative polarity when contact 123 connected with terminal 116 is connected with negative contact 124 of the polarity reversing switch as shown in Fig. 2.

The means for connecting the various stationary contacts of the polarity reversing switch comprises a disc 130 insulatingly supporting three metal segments 131, 132 and 133. These segments are of sufficient arcuate length to bridge the stationary contacts which are located 60° apart. Hence the movable contacts are located equiangularly distant at 120°. The disc 130 is fixed to a shaft 135 carrying a ratchet 136 having six equiangularly spaced teeth 137. The teeth 137 are engageable by pawl 138 pivoted upon a rocking lever 139 loosely journaled on the shaft 135. Lever 139 is provided with a fork end 140 engageable with a pin 141 carried by the link 62 which connects the plunger 61 with the starter drive shift lever 34. To prevent backing up of the pawl 138, there is provided a leaf spring member 142 which is fixed at 143 and is engageable with any of the teeth of the ratchet 136.

When the starting circuit is closed by closing the ignition switch and by closing the accelerator pedal switch 80, the plunger 61 not only moves to effect the starter function, but also to rotate the shaft 135 a distance of 60° so as to move the disc 130 and contacts carried thereby from a position such as shown in Fig. 1 to a different position such as shown in Fig. 2 thereby causing the polarity of the ignition timer contacts 114 and 115 to be reversed. Therefore during each function of the starter as effected thru the electromagnet 40 there will be a reversal of polarity of the ignition timer contacts.

I arrange the wiring of the ignition system in such manner and I select a timer condenser 118 of such capacity that at no time during the operation of the ignition system will there be a positive transfer arc occurring at the ignition contacts at the time of secondary discharge. I use a fast operating breaker lever so as to make the contact gap as large as possible during the secondary discharge and I use a timer condenser 118 of such capacity as to retard the rate of secondary build-up to such extent that the primary induced voltage at the time of secondary discharge will be always less than that required to start a positive contact transfer arc. Also I separate the primary and secondary leads from the ignition coil to such extent and may even place them into such close proximity with ground as to prevent any transient voltage derived from the high frequency oscillation occurring secondary discharge from reaching such a value that, when added to the primary induced voltage, the resultant voltage would be sufficient to start a positive transfer arc. For example, I disclose in my copending application that about 340 volts at the contacts is necessary to start a positive transfer arc. I so arrange the circuit and so select the condenser 118 that the sum of primary induced voltage and transient voltage at the time of secondary discharge is always substantially below 340 volts. In this way I eliminate the occurrence of positive transfer arcs and deal only with the negative transfer problem which is I believe less severe. By reversing polarity at frequent intervals in a system where only negative transfer can occur I am able, at least with passenger car ignition operating on 6 volts, to effect the substantial balance between negative transfer in one direction and negative transfer in the opposite direction. Therefore I am able to effect substantially flat contact operation in certain types of ignition systems.

While the embodiment of the present invention

as herein disclosed constitutes a preferred form, it is to be understood that other forms might be adopted, all coming within the scope of the claims which follow.

What is claimed is as follows:

1. In an engine starting and ignition system for internal combustion engines, the combination of a current source and electrical ignition apparatus including timer contacts, an engine starting device including an electric motor, electromagnetic means for electrically connecting the motor with the current source and for mechanically connecting the motor with the engine, a relay for connecting the electromagnetic means with the source, a switch for reversing the polarity of the current delivered from the current source to the timer contacts, and means for automatically operating the switch in response to the operation of the electromagnetic means.
2. In an engine starting and ignition system for internal combustion engines, the combination of a current source and electrical ignition apparatus including cooperable timer contacts, an engine starting device, a solenoid switch for connecting the starting device with the source, and including a relay, means for energizing the relay only when the timer contacts are conditioned for current conduction, a switch for reversing the polarity of the current traversing the timer contacts, and means for operating the reversing switch automatically in response to operation of the solenoid switch, whereby the polarity of the current traversing the timer contacts will be reversed each time the solenoid switch is closed.
3. The combination set forth in claim 2, wherein the solenoid switch and relay are entirely disconnected from the current source when the engine becomes self operative.
4. In an engine starting and ignition system for internal combustion engines, the combination of a current source and electrical ignition apparatus including cooperable timer contacts, an engine starting device, a solenoid switch for connecting the starting device with the source, and including a relay, means for energizing the relay only when the timer contacts are conditioned for current conduction, a switch for reversing the polarity of the current traversing the timer contacts, and means for operating the reversing switch automatically in response to operation of the solenoid switch, whereby the polarity of the current traversing the timer contacts will be reversed each time the solenoid switch is closed, and means preventing connection of the solenoid switch with the current source while the engine is self operative.
5. In an engine starting and ignition system for internal combustion engines, the combination of a current source and electrical ignition apparatus including timer contacts, an engine starting device including an electric motor, electromagnetic means for electrically connecting the motor with the current source and for mechanically connecting the motor with the engine, a relay for connecting the electromagnetic means with the source, a switch for reversing the polarity of the current delivered from the current source to the timer contacts, and means for automatically operating the switch in response to the operation of the electromagnetic means and means for automatically disconnecting the electromagnetic means from the current source directly that the engine becomes self operative.
